UNITED STATES PATENT OFFICE.

CLARKE P. POND, OF PHILADELPHIA, PENNSYLVANIA.

BUILDING CONSTRUCTION.

1,074,526.

Specification of Letters Patent. Patented Sept. 30, 1913.

Application filed June 1, 1912. Serial No. 701,085.

To all whom it may concern:

Be it known that I, CLARKE P. POND, a citizen of the United States, residing in Philadelphia, Pennsylvania, have invented 5 certain Improvements in Building Construction, of which the following is a specification.

One object of my invention is to provide a novel building construction particularly 10 designed for the purpose of preventing accumulation of gases in its upper part and to assist in the removal of such gases; the arrangement of the parts being such as to provide a substantially uniform distribution of 15 daylight and fresh air throughout the entire width of the building.

I further desire to provide an improved 20 form of building construction which shall include a monitor roof of novel form especially designed with a view to carrying away rain water in the most satisfactory manner and at the same time provide the most advantageous distribution of light as well as the most effective ventilation for the building.

25 These objects and other advantageous ends I secure as hereinafter set forth, reference being had to the accompanying drawings, in which:

Figure 1, is a transverse section of a building 30 constructed according to my invention, portions of the side extensions of the building being omitted; Fig. 2, is a transverse vertical section of one side of the building shown in Fig. 1, and Fig. 3, is a vertical section on an enlarged scale illustrating the detail construction of the sides of the monitor.

The building constructed according to my 35 invention is to be understood as provided with any suitable number of sets of roof trusses with their necessary columns, ties, and struts placed at proper intervals, as is well understood by those skilled in this particular art; the drawings illustrating one such set of parts as found in a single plane 40 extending transversely of the building.

In the above drawings 1 represents a central 45 vertical column while 2 indicates the columns at the extreme sides of the building, although it is to be noted that said columns 50 may be in other positions as may be required for the support of traveling cranes, or for other purposes, without departing from my invention. These columns serve to support the horizontally extended roof truss 3 which 55 has upper and lower chords 4 and 5 con-

nected by vertical and diagonal members 6 and 6^a as shown.

The central column 1, or its equivalent structure, has a vertical extension 7, and at a distance on either side of the line of said column equal to approximately one-third of the distance between it and one side of the building, I provide light columns or struts 8 which extend to a height above that of the central column 7, to which they are connected by suitable trusses 9. The upper portion of the column extension 7 is connected to the upper chord 4 of the truss 3 by tie rods 10 at points adjacent the bases of the columns 8.

The columns 7 and 8 with the trusses 9 of the various sets of transverse elements constitute a frame for a monitor and these are connected by longitudinally extending rafters 11, on which is mounted the monitor 75 roof 12, which, owing to the construction heretofore described, slopes from its edges toward its center which is in the vertical plane including the various columns 7.

From a point above the middle of each of 80 the columns 8, structural members 13 extend downwardly at an angle of about 30 degrees to the vertical to the upper chord member 4 of the truss 3, and the outer portions of these latter trusses are likewise connected 85 together by longitudinally extending rafters 14 on which is mounted the roof proper 15. The supports for this latter are of such design that its outer portion (equal to about one-quarter of its width) slopes inwardly 90 from its edge, from whence the roof slopes upwardly to the bases of the inclined members 13 on which it extends for a short distance.

The inclined members 13 as well as the 95 upper halves of the columns 8, with the longitudinal members 16—19, constitute an open framework which serves for the support of two lines of outwardly swinging sashes 20 and 21, one above the other between the 100 longitudinal members 16 and the top of the monitor roof, and likewise for two sets of the sashes 21 between said member 16 and the upper edge of the roof structure 15.

The various sashes are pivotally mounted, 105 hung or hinged at their upper edges and may be provided with any suitable means whereby all the sashes in each line can be simultaneously swung out to the open position indicated in dotted lines in Fig. 1.

The various columns 2 are likewise connected by a series of horizontally extending members 22 which are provided with the necessary vertical members to form a series 5 of window frames, of which the windows of the upper two sets 23 are arranged in two lines designed to swing outwardly from their upper edges. The lower portions of these windows are provided with vertically 10 movable sashes 24, so that the entire area of each side of the building from the roof 15 downwardly, as well as practically the entire area of both sides of the monitor, are formed for the admission of light. It is 15 further to be noted that with the monitor construction described it is an impossibility for objectionable gases to accumulate in the building when the windows are open, for the inclination of the roof 12 is such that 20 rising gases are at once directed outwardly to one side or the other of the building instead of accumulating in the upper part thereof as in the ordinary construction, and thereafter falling into its lower portions 25 when they become cooled.

Owing to the peculiar arrangement of the windows in the side portions of the monitor, the central parts of the building are illuminated in the best and most efficient manner, 30 as are also those other parts immediately under the roof 15, owing to the light delivered through the windows 23 and 24 as well as to that admitted through the windows in the sides of the monitor. The peculiar arrangement of the windows 20, 21 and 23 is such that these may be kept open even during severe storms.

The construction of the monitor roof 12

in the manner shown, makes it possible to remove all the water falling on or delivered 40 upon said roof through suitable drain pipes (not shown) arranged to collect the same from its central depression, thus avoiding delivery of water upon the laterally extending roofs 15.

45
I claim:—

1. A building having a monitor, the upper part of the sides of said monitor being substantially vertical and the lower parts thereof being outwardly inclined to the 50 main roof of the building, said sides being for the greater part formed by windows.

2. A building having a frame formed of a series of substantially parallel elements, each of said elements consisting of columns, 55 a truss carried by said columns; a central column; auxiliary columns supported by the truss and extending vertically to a height above the central column; means for connecting said auxiliary columns with the 60 central column; longitudinally extending members connecting the various elements of the frame; a roof sloping from points above the auxiliary columns downwardly to the central columns; and main roofs extending 65 respectively from points adjacent the bases of the auxiliary columns outwardly to the sides of the building.

In testimony whereof, I have signed my name to this specification, in the presence 70 of two subscribing witnesses.

CLARKE P. POND.
